DESIGN FOR A TEXTILE FABRIC OR SIMILAR ARTICLE OF MANUFACTURE

Emmanuel M. Cohen and Jesse Olenick,
New York, N. Y.

Application September 4, 1935, Serial No. 58,435

Term of patent 3½ years

To all whom it may concern:

Be it known that we, Emmanuel M. Cohen and Jesse Olenick, both citizens of the United States and residents of the city of New York, Borough of Manhattan, county and State of New York, have invented the new, original, and ornamental Design for a Textile Fabric or Similar Article of Manufacture, of which the following is a specification, reference being had to the accompanying drawing, forming part thereof, in which

The figure is a plan view of a piece of textile fabric embodying our new design, a repeat unit of which is outlined on the drawing by dot and dash lines.

We claim:

The ornamental design for a textile fabric or similar article of manufacture as shown and described.

JESSE OLENICK.
EMMANUEL M. COHEN.
